UNITED STATES PATENT OFFICE.

JNO. N. ARVIN AND SAML. H. PERKINS, OF VALPARAISO, INDIANA.

SETTING AXLETREES.

Specification of Letters Patent No. 29,132, dated July 17, 1860.

To all whom it may concern:

Be it known that we, JOHN N. ARVIN and SAMUEL H. PERKINS, of Valparaiso, in the county of Porter and State of Indiana, have 5 invented a new and useful Machine for Setting Axletrees for Wagons and other Vehicles; and we do hereby declare that the following is a full, clear, and exact description of the construction and operation of 10 the same, reference being had to the annexed drawings, and letters of reference marked thereon, making a part of this specification.

Figure 1, is a perspective view of the whole machine, in which *f*, represents the 15 bench; *A*, *A*, the rests; *C*, *C*, the sets, and *d* the set screws with cranks. Fig. 2, represents the sections marked *C*, *C*, in Fig. 1, to be further described, and Fig. 3 represents profile views of Fig. 2, marked *C'*, and pro- 20 file views of sections *A*, *A*, Fig. 1.

Referring to Fig. 1, the bench *f*, is made of a squared piece of timber 6 feet long, and 4 inches thick and 6 inches wide, set upon legs of proper height, and firmness. The 25 rests *A*, *A*, Fig. 1, and *A'*, Fig. 2, are made of cast iron 6 inches high, 3 inches wide and $\frac{3}{4}$ inch thick with ears extending upward about 2 inches, to receive the set screws *d*. The rests are fastened to the bench by $\frac{1}{2}$ inch 30 iron bolts, and can be moved or graduated so as to rest immediately under the shoulders of the axletree to be set. The sets *C*, *C*, are of cast iron, and are fastened to the bench in the same manner as the rests, and are 35 composed of two parts, the standards *D* in Figs. 2 and 3, which are 4 inches high to

lower part of rings *B*, *B*, and are of the same width and thickness as the rests. The gages, Figs. 1 and 2, are 3 inches in length to the rings *B*, *B*, with their lateral edges 40 flanged to receive the standard, and are fastened together by the set screw *e* Fig. 1. The rings *B*, *B*, are 3 inches in diameter, 1 inch wide and $\frac{3}{4}$ inch thick, and are pierced by the set screws *d*. 45

Directions for use.—Place a straight edge on the rests *A*, *A*, extending through the rings *B*, *B*, lower the set screws *d'* as much below the straight edge as you wish to give pitch to the axle, set the lateral set screws, 50 *d''* by the assistance of the straight edge a sufficient distance back, to give the desired gather; heat the axletree at the shoulders, place it on the rests *A*, *A*, the ends extending through the rings *B*, *B*, then fasten the axletree at *A*, *A*, with the set screws *d*, *d*, then turn the set screws *d*, *d*, in the rings *B*, *B*, until the points of the axel come in contact with the set screws *d'* and *d''*. 55

What we claim as our invention and desire 60 to secure by Letters Patent, is—

An improved mode of setting axletrees, and giving them the required "pitch" and "gather" by means of metallic set screws, 65 rests, and sets, or their equivalents, as exhibited, and described by the specifications herewith.

J. N. ARVIN.
S. H. PERKINS.
